UNITED STATES PATENT OFFICE.

LUCAS MAURER, OF BOSTON, MASSACHUSETTS.

FLYING-MACHINE.

1,119,710.

Specification of Letters Patent.

Patented Dec. 1, 1914.

Application filed March 11, 1914. Serial No. 824,025.

To all whom it may concern:

Be it known that I, LUCAS MAURER, a citizen of the United States, and a resident of Hyde Park, Boston, county of Suffolk, and 5 State of Massachusetts, whose post-office address is East Dedham, Massachusetts, have invented an Improvement in Flying-Machines, of which the following description, in connection with the accompanying drawings, is a specification, like characters on the drawings representing like parts.

My invention relates to flying machines and has particular reference to that part of the machine which is depended upon largely 15 to furnish stability and sustaining power, and commonly termed the wing or plane.

At the present time it is common practice to provide the body with planes of suitable material extended laterally from each side 20 of the body, which planes are sometimes movable vertically, more or less, relatively to each other to assist in guiding the machine upward and downward. In all such machines the center of gravity is relatively 25 near the top plane and as a consequence the machine is easily overturned by a sudden gust of wind and is, at all times, difficult to manage for this reason.

I have invented an improved construction 30 of flying machine which overcomes this difficulty and among other novel features possesses planes of unusual sustaining power.

In the drawings of an illustrative embodiment of my invention described herein, 35 Figure 1 is a side elevation thereof; Fig. 2, a detail of the clutch mechanism for operating the planes, and Fig. 3, a further detail of the operating mechanism.

Referring to the drawings, Figs. 1, 2, my 40 improved flying machine may comprise a frame or body 1, of suitable conventional construction. This body or frame may be provided with a usual engine 2, for operating, by any convenient means, the propellers 45 3, 3, also of usual construction and the body may also be provided with a vertical rudder 4, and horizontal rudder 5. As no novelty is claimed in respect of either of these members, their detailed illustration or description 50 is not necessary. Substantially vertically positioned relative to the car 1, and disposed at suitable points longitudinally thereon, are two plane-bearing or supporting posts or sleeves 6, 7, which may be rigidly held in position by guys or stays 8, 8, 55 secured at their lower ends to the body.

Within each of these posts is rotatably mounted a shaft 9, 10, in suitable bearings, and provided each, at its top, with a substantially circular umbrella-like plane or 60 disk 11, 12, of suitable material, as aluminum. These planes may be properly strengthened and supported by ribs 13 and stayed by stays or guys of wire or other material 13 to make them preferably, very 65 rigid so that they will not buckle when ascending against a strong pressure of air. I have found by experience that by rotating these planes rapidly, it adds much to their sustaining power, presumably because, when 70 so rotated, the stratum of air immediately beneath them is compressed and its resistance to the descending planes is thereby increased. Inasmuch, also, as the sustaining power of the disks or planes is increased by 75 making them convex, in my opinion, because such form tends to confine the air more or less beneath the plane and to compress the air more when the planes are rotated, they are preferably made convex to any desired 80 degree, but I have found if deflected in about the ratio of one inch to fourteen inches of diameter, they give good results. I have also found that a diameter of twenty feet for each plane is a satisfactory and conven- 85

ient size. While I have shown herein two planes, one only may be used for a small machine. For operating these disks, I have provided at the lower end of each shaft 9, 10, a bevel gear 14, in mesh with and 90 adapted to be rotated by opposed bevel gears 15, 16, loose on a shaft 17, rotated by a gear 18 thereon in connection with the gear 19 on the main shaft 20 of the engine. On the shaft 17 and between each pair of loose 95 gears 15, 16, is mounted a clutch collar 21 adapted to engage a coöperating clutch member 22 on the inner face of each of the gears 15, 16. This collar 21 has a circumferential groove 22' in which is received one 100 end of a lever 23 pivoted at 24 and connected at its opposite and lower end to a link 25 adapted to be actuated by a lever 26 conveniently located for the operator.

Each plane is controlled by a separate 105 lever so that each may be operated independently if desired, as shown in Fig. 3. Obviously by throwing the hand lever 26 to cause the clutch lever 23 to lock the collar 21 to the gear 15, the plane will be rotated in one direction, while if the lever 26 is thrown to lock the collar to the opposite 110

gear 16, the plane will be rotated in the opposite direction.

I have discovered that by simultaneously rotating the planes in the same direction, 5 they assist in propelling the machine, while if they are simultaneously operated in opposite directions, they retard the progress of the machine. If the propeller is stopped and the planes are rotated in opposite directions, 10 they tend to neutralize the effect of the wind current and, if it is not too strong, they will substantially hold the machine at rest, in so far as travel is concerned. Of course the machine is guided mainly by the two rudders. In a machine 15 constructed as herein described, it will be evident that the center of gravity is far below the planes 11, 12, and therefore the danger of overturning is reduced to a minimum. It is a well known fact that a disk or 20 plane of thin, stiff material may be propelled through the air edgewise for a long distance, the flat plane being buoyed up by its proportionally large air-engaging area as compared with its weight, and I have 25 discovered that such bodies have great sustaining power. I have also discovered that planes curvilinear in form, similar to that illustrated herein, may be propelled with the expenditure of much less force than can a plane the edge of which is substantially straight. This I understand to be 30 because the air-cutting edge of the plane is brought substantially to a point, and it cuts progressively as distinguished from an 35 edge that cuts all at once throughout its length, on the same principle that a point of a knife can be thrust into a mass of material farther than can the whole cutting edge of the knife be so thrust at once. On 40 this account also the machine is more easily guided as it responds more gently and with less abruptness to the manipulation of the rudder following the narrow air-splitting edge of the curvilinear plane than it does 45 following the relatively long straight air-

splitting edge of the conventional flat plane. I have also discovered that by rotating the planes the natural tendency of the machine to drop, when the propeller is not running, 50 is greatly retarded and a descent can be effected much more gradually and safely than it can be with a machine equipped with the common or usual form of planes.

This form of plane also possesses another great advantage, viz: even though it be badly damaged, as by having many holes made in it, for instance by bullets, it does not lose all its effectiveness but it may still be used with good results. This 60 feature therefore makes it particularly valuable for use in constructing machines for use in war time when they are particularly subject to damage.

Having described one form of my invention which, however, may doubtless be varied in many details without departing from the spirit thereof, and within the scope of the appended claim, I claim:

A flying machine having a substantially 70 cigar-shaped frame, plane supporting members thereon in substantially the central longitudinal plane thereof, movable curvilinear planes thereon, a gear on each supporting member, a plurality of loosely 75 mounted gears in mesh therewith and provided with clutch members, a clutch member disposed between said loosely mounted gears and provided with means for throwing it into engagement at will with either 80 of said gears, motive power connected with said gears for driving the same and a plurality of propellers intermediate the ends 85 of said frame and between said planes.

In testimony whereof, I have signed my name to this specification, in the presence of two subscribing witnesses.

LUCAS MAURER.
